APPARATUS FOR MAKING PILE FABRICS

Victor A. Victor, Brooklyn, N. Y.

Application September 16, 1944, Serial No. 554,405

14 Claims. (Cl. 154—1.1)

1

The invention relates to an apparatus for making a pile fabric or product constituted of a flexible backing upon which is deposited, in substantially upright position, any character of pile forming material, and permanently embedded into an adhesive composition coating the flexible backing.

The invention, more particularly, consists in the provision of an apparatus for making such pile products on a commercial scale, and with a substantially continuous operation of such apparatus, whereby the yield of pile fabric from the apparatus is sufficiently large and the pile product is produced at a sufficiently rapid pace to make the utilization of such apparatus on a commercial basis favorably competitive with the ordinary commercial embodiments of other types of pile fabric producing apparatus.

Reference is made to my copending application Serial No. 439,579, filed April 18th, 1942, now Patent No. 2,358,368, dated September 19, 1944 in which I disclose a method and Apparatus for making pile fabrics, and upon the apparatus of which application the present apparatus is an improvement.

In such copending application, I have disclosed an apparatus for producing a pile material in which apparatus, however, there is incorporated a single and individual mechanism for applying a plurality of fiber elements to constitute the pile to the backing at the pile forming station.

In the present application, on the other hand, I shall describe, in conjunction with the accompanying drawings, a commercial embodiment of my apparatus which is so constructed as to operate on a cyclic basis, utilizing a single pile forming station but a plurality of sets of mechanisms for bringing the pile forming material to such station, whereby the capacity and speed of the apparatus is greatly increased and a substantially continuous operation of pile forming

In addition to the provision of mechanism for the cyclic operation of particular elements of my apparatus, there are incorporated in the new and commercial embodiment of my invention, as hereinafter disclosed, a number of improvements, both in the mechanism and controlling elements thereof and in the actual structural design of various components of the apparatus to make the assembly smooth in operation and to have a substantially continuous yield of pile product from the substantially continuously operating machine elements.

The primary and distinguishing feature of an apparatus for forming pile fabric, as herein dis-

2

closed, is the use of what will be hereinafter termed "a drum," which comprises a rotating element from which extend radially a plurality of pile element grasping mechanisms. Such mechanisms, upon the step-by-step rotation of the drum, grasp the leading edge of a line of fabric elements severed from their source of supply and then transfer the severed predetermined length of fiber elements to a pile forming station and thereafter cause the embedding of such pile elements into the cementitious coating spread uniformly upon a flexible backing.

The utilization of such rotating drum involves also the provision of certain novel mechanism for its control and movement and the present application discloses such control mechanism, for instance, a locking lever and bumper hook for such drum.

In my novel commercial embodiment of apparatus for forming pile fabrics there is incorporated also a somewhat different type of jaw-closing and jaw-opening device from that disclosed in my prior copending application, as well as a modified form of knife holder and knife operating mechanism.

Various other improvements in the apparatus are illustrated in the accompanying drawings and will be described hereinafter in conjunction with the exposition of the specific pile forming apparatus shown in such drawings.

In the following description of the particular commercial embodiment of my apparatus illustrated in the accompanying drawings, it will not be necessary to describe in detail those elements of the apparatus which are substantially identical or very slightly different from the specific embodiment of the similar, but single operative, embodiment of the apparatus shown and described in my said copending application.

Wherever, however, the description of such mechanism, even though illustrated and described in said copending application, is deemed necessary for an understanding of the operation of my present commercial embodiment of the apparatus, such parts and mechanism will be again, however briefly, referred to.

In the accompanying drawings, Fig. 1 is a side elevation of the actual commercial embodiment of an apparatus, for forming a pile fabric, constructed in accordance with my present invention; Fig. 2 is an end elevation of such apparatus, the view being broken centrally of the machine, but showing all essential parts thereof in full; Fig. 3 is a side elevation on a somewhat enlarged scale with a portion of the frame of the appa-

ratus removed; Fig. 4 is a side elevation of the drum by the utilization of which the continuous "cyclic" operation of my apparatus is obtained, showing also the mechanism for opening the jaws grasping the pile forming elements; Fig. 5 is an enlarged detail of the mechanism at the lower right hand portion of Fig. 4, showing the pile grasping jaws in their open position; Fig. 6 is an elevation of part of the mechanism shown in Fig. 5; Fig. 7 is an enlarged end elevation of the pile grasping jaw closing mechanism; Fig. 8 is a side elevation of the jaw closing mechanism of Fig. 7; Fig. 9 is a section on the line 9—9 of Fig. 3; Fig. 10 is an enlarged detail of the drum advancing pawl; Fig. 11 is an enlarged detail of the drum locking pawl; and Fig. 12 is an enlarged detail of the mechanism for controlling the cutting action of the knife and the raising thereof from its pile element cutting position (the portion of the mechanism shown at the upper left hand part of Fig. 3).

Referring more particularly to the drawings, in which similar reference characters identify similar parts in the several views, the general relation and character of the various elements constituting my novel apparatus are best illustrated in the assembly or slide elevational view of Fig. 1, and the end elevational view of Fig. 2. In such figures, 13 is the main frame upon which the machine elements are supported, the main driving element, an electric motor 14, being suitably disposed upon the frame below the pile forming mechanism, the main driving pulley 15 and belt 16 being shown in Fig. 1.

The main driving pulley 15 drives, by its belt 16, a wheel 17, upon the shaft 18 of which is secured, by an eccentric wheel 19, one end of a link or arm 20, the other end of the link or arm 20 being secured in a slot 21 of a rocker arm 22 pivoted at 23 and carrying at its outer end a pawl 24. The movement of such rocker arm 22 causes the periodic rotation or advancement of the wooden roller 25 by which the finished pile product is drawn from the apparatus, the roller being provided with conventional carding wire teeth 26. The roller 25 constitutes a carding wheel which advances the backing strip through the apparatus from which carding wheel the finished product is then led to the vulcanizing oven and pertinent parts not herein further described as they are shown and described in my aforesaid copending application.

Coming now to the description of the pile forming mechanism, such mechanism is constituted of a drum generally designated as 27 which, in the illustrated embodiment of my invention comprises eight pile gripping jaw mechanisms radially disposed within and extending from said drum.

The rotation or step-by-step advancement of the drum 27 is accomplished as follows:

Upon the shaft 18 and adjacent the pulley 17 is a smaller pulley 28 from which extends a sprocket chain 29 rotating a sprocket wheel 30 mounted upon a shaft 31. From the shaft 31 extends an arm 32 to which is connected the end of a link 33. The upper end of such link 33 is in turn connected to an arm 34 mounted on the main shaft 35 of the drum 27. As the link 33 moves vertically, it causes the rotation, through the intermediary of arm 34 extending from the shaft 35, of the drum 27. The extent of the rotary movement of such drum is governed by a cam 36 which has four notches therein. The

pawl 37, mounted on arm 34 controlled by a spring 38, is adapted to enter one of the four notches in the cam. Upon the shaft 35 is mounted a large gear 39 meshing with a pinion 40, causing a change in the direction of the rotation in the drum from that of the cam and large gear 39. On the same shaft that carries the pinion 40 is a pinion 41 meshing in turn with an internal gear 42. The ratio of the gears 39, 40 is such as to cause the rotation of the drum $\frac{1}{8}$ of a revolution, each time the cam 36 is rotated $\frac{1}{4}$ its revolution.

On the shaft 35 of the drum 27, is a large disc 43 having eight notches 44 therein by which is adapted to be caught a bumper hook 45 herein-after described in greater detail. The disc 43 is likewise provided with eight locking recesses 46 in which a locking lever 47, also described in greater detail hereinafter, is adapted to be seated. On the shaft 35 is a fixed cam 48 having a raceway 49 in which rides rollers 50.

Radially disposed within the rotating disc 43 are slots 51, through which extend arms 52 which carry at their farther ends the jaw mechanism generally designated as 53.

Turning now to a description of the mechanism for controlling the rotational movement of the drum 27, the bumper hook 45 is shown in enlarged detail in Fig. 10. Such bumper hook is pivoted upon the shaft 54 riding in a block 55 controlled by a compression spring 56. The rocking of the bumper hook 45 about the shaft 54 is accomplished by means of an arm 57 pivoted upon shaft 58 and carrying at its free end a roller 59. The shaft 58 is connected to the rest of the structure in order to properly time the release of the hook 45 or of the hook 47 by means of the chain extending over the various sprockets illustrated at the upper righthand portion of Fig. 3, including the sprocket of shaft 58. Such shaft is therefore periodically rotated by said chain. Each time the drum 27 completes its $\frac{1}{8}$ revolution the bumper hook 45 engages, by its nose 60 within the notch 44 of the disc 43. The bumper hook is effective to position the drum 27 at the exact necessary degree of its rotation, so as to bring the jaw mechanism 53 to the pile severing station and to enable such jaw mechanism to grasp the line of tufts severed from the supply of pile material at the severing station.

The disc locking lever 47 pivoted upon the shaft 54 is controlled in similar manner by the link 57 and roller 59. The locking lever 47 has its nose 61 formed to enter the locking slots or recesses 46 thereby effecting the positive locking of the disc 43, and therefore of the drum 27, in the exact position of such drum required for the proper positioning of the jaw mechanism 53 at the pile severing station.

The fixed cam 48 is effective to cause the radial movement of the arms 52 along the slots 51. As the disc 43 rotates, the rollers 50 for each of the jaw mechanisms 53 travel in the raceway 49. The raceway 49 is so designed as to cause the radial outward movement, to its remotest position, of each jaw mechanism at the exact moment when such jaw mechanism is opposite the pile severing station. Such disc 43 continues to rotate in the direction of the arrow in Fig. 3, the movement of the roller 50 of each jaw mechanism in the raceway 49 causing the movement radially of the jaw mechanism at the end of each arm 52 until at the bottommost position of each 75 jaw mechanism, i. e., at the pile depositing sta-

tion after deposit of the pile, the roller travels upwardly in the raceway 49 to a sufficient extent to bring the jaw mechanism completely out of its position adjacent the backing at the pile depositing station.

The jaw opening device is illustrated in enlarged detail in Fig. 5 and in association with the remaining mechanism, in Fig. 3. Such jaw opening device comprises a pivoted lever 62 pivoted upon the shaft 63 and having a hook nose 64 on one end, and an abutment ledge 65 at its opposite end. The ledge 65 is adapted to be engaged by a roller 66 mounted upon the high dwell portion of a cam 67 secured upon a shaft 68. The shaft 68 is rotated by a gear and chain mechanism shown generally at the upper right hand portion of Fig. 3, which need not be described herein in any great detail, as the various driving mechanisms for the various elements of my apparatus are shown in the accompanying drawings by way of illustration rather than by way of limitation.

As the jaw mechanism 53 reaches the pile depositing station immediately above the backing strip 69 fed through the apparatus as hereinafter described, and has deposited the line of tufts previously grasped at the severing station and brought to the pile forming station, the jaw opening device operates to open the jaws and release the pile forming elements which have been embedded in the cementitious coating of the backing strip 69. The opening of the jaws is accomplished as follows: As the shaft 68 is rotated, the roller 66, hitting contact shoe 65, of the lever 62, causes the nose 64 to abut the pin 79 of the jaw trigger disc 70 the upward movement of which causes the jaws to open by pushing one of the jaws sidewise.

The jaw closing device is illustrated in Figs. 7 and 8, and comprises a trigger disc 70 having a notch 71 in which rides a pin 72 controlling the closing of the jaws.

As shown in Figs. 7 and 8, the arm 73 which is attached to the knife holder 99 by screws 200, carries at its lower free end a roller or other detent mechanism 74 which upon the movement downwardly of the arm 73 abuts the roller 75 at the end of an arm 76 of a fulcrumed lever and causing the other arm 77 of such fulcrumed lever to abut, by its tongue 78 a roller 79 on the trigger disc 70. The pin 72 travels in the notch 71 which is provided for the purpose of controlling the time of closing of the jaws therefor by first giving free play to the closing mechanism and as the disc 70 rotates the impact of the pin 72 against the lower side of the notch 71 causes the jaw closing mechanism to operate instantaneously.

The backing strip 69, which is to constitute the backing for the pile fabric produced by my apparatus, is supplied from a roll 80 of such material and passes through the apparatus as shown in dot and dash lines in Fig. 1. The backing strip is first brought to a point of deposit of a uniform coating of cementitious material on the upper surface thereof in any conventional manner, for instance, by a device such as is disclosed and described in my copending application. The backing strip is then brought across the apparatus to the pile depositing station where, after being brought momentarily to rest upon a table surface 81 at the exact point of deposit of pile forming elements thereof, it is given an abrupt downward turn and then passes over the carding wheel 25.

The pile forming material generally designated as 82 passes through the apparatus as shown in the dot and dash lines at the top of Fig. 1. The

feeding of such pile forming material is accomplished as follows:

From the shaft 18, by the train of pulleys and V-belts shown in detail at the bottom of Fig. 1, which in turn rotate a gear train mechanism 83, the yarn or other pile forming material 82 passes over the pulley 84 and then downwardly under pulley 85, upwardly over pulley 86, and then down to pulley 87; thence transversely of the apparatus 10 through the reed 88 to the pile severing station. The pile severing station comprises a table surface 89 upon which the yarn or pile supply rests and is grasped by the downward movement of an L shaped arm 90 which moves slightly forward 15 with the pile forming material and when the leading edge of the pile elements have been severed, moves slightly upwardly and backwardly. This movement of the L shaped arm 90 is controlled by cam 91 and vertical lever 92 which carries at 20 its lower end roller 93, rotating along the surface of cam 91.

Cam 91 controls the upward movement of the L-shaped arm 90. The eccentric 100 and its link 101, connected to the lever 102, (shown in dotted lines in Fig. 3) returns the L-shaped arm 90 to its laterally outward position. As cam 91 rotates, its low-dwell surface causes a downward movement of the arm 92, thereby permitting the L-shaped arm 90 to grasp the pile forming elements. After such grasping of the pile forming elements by the L-shaped arm 90, the eccentric 100 and its link 101 move the lever 102 forwardly, the L-shaped arm 90 and table 89 moving forward a corresponding distance.

35 The slight axial movement of the pile grasping mechanisms outwardly at the pile forming station to deposit the pile upon the backing is accomplished as follows: As will be seen in Figs. 4 and 5, a triangular lever 103 is pivoted on a short 40 shaft 104 extending through the apparatus, the roller 105 at one extremity of such triangular lever riding upon the faces of cam 106. Such cam 106 has cam faces, one, 107, of larger diameter and the other, 108, of smaller diameter, as 45 clearly shown in Fig. 5. On the other end of the short shaft 104 is a finger 109. As the drum 27 rotates, the arm 52, when it reaches the point of deposit of the pile elements upon the backing, is started by such finger 109. As the cam 106 rotates, the second or larger radius face thereof, 107, causes the finger 109 to depress the arm 52. After the deposit of the pile elements is made, the jaw opens and the arm 52 is withdrawn.

The pile severing mechanism comprises a shear- 55 ing plate 94 and a knife 95 vertically movable by the long link 96, shown in Fig. 3, in its position of actual severing by the knife of a line of tufts from the supply of pile forming material. As the knife 95 has severed a line of tufts from the supply of pile forming material, such line of tufts is grasped by jaw mechanism 53 brought to its exact pile grasping position by the drum 27 and the jaws of the jaw mechanism 53 are closed. The 60 rotation of the drum 27, $\frac{1}{8}$ its revolution carries the now closed jaws a distance one-half circumferentially of the drum between the severing station and the pile depositing station. It will be understood, of course, that as the jaw mechanism 53, which has just grasped a line of tufts, is moving down to a position $\frac{1}{8}$ of the total revolution of the drum 27, another jaw mechanism 53 has just reached the pile depositing station and is depositing the line of tufts grasped by it into the cementitious coating of the backing material.

The operation of the knife 95 is accomplished as follows:

As the eccentric shaft 97 rotates, the link 96 moves vertically. The link, of which there are two, one on each side of the machine, is anchored at its top in a boss 98 protruding from a transversely extending knife holder 99, to which the knife blade is removably secured by a plurality of nuts and bolts. The blade itself is preferably secured to the holder at a slight angle 10 through its length, so that upon its descent it severs the leading edge of the pile forming material with a shearing action.

From the above general description, which has been made purposely schematic, it will be seen that I have illustrated and described in the present application an embodiment of my pile forming apparatus heretofore described with respect to its general organization in my aforesaid pending application, but which present apparatus operates substantially continuously on a "cyclic" principle. This is accomplished by providing a plurality of pile grasping and depositing instrumentalities upon a rotating drum in such manner that at the same time that a line of tufts is being grasped by one jaw mechanism at the pile severing station, another jaw mechanism is already in position and effecting the deposit of a previously grasped line of tufts of pile forming elements. Thus, I have illustrated in the commercial embodiment of my apparatus hereinabove described, a rotating drum having eight radially disposed jaw mechanisms. The number of such radially disposed pile grasping mechanisms which may be incorporated in a rotating drum is limited only by the desired size of the apparatus and the speed with which the various component parts of the mechanism can be designed to accomplish their individual functions. Thus, it is entirely within the skill of a designer of an apparatus constructed in accordance with my invention to utilize a drum of any multiple of two or more jaw mechanisms upon a single drum.

It will be recognized from an inspection of the drawings that what I have called hereinabove a "drum" is a rotating element of open spider construction, rather than a substantially completely closed tubular element. The word "drum" in the above description is to be interpreted to mean such open rotating element.

I claim:

1. An apparatus for producing a pile material, which comprises means for feeding a flexible backing, uniformly coated with a cementitious composition, to a pile forming station, means for feeding a supply of fiber elements to constitute the pile to a severing station, means for severing a predetermined length thereof from the fiber elements, and a plurality of means arranged in series comprising a plurality of pairs of jaws radially disposed for operative action on a rotating drum, for grasping said severed fiber elements in successive series thereof, and for moving such severed elements in such series, to a substantially vertical position with the lower free ends thereof at substantially right angles to and spaced from the point on the backing at which said pile-forming elements are to be deposited, at the same time another fiber grasping means is brought to a position adjacent the severing station, and means for thereafter imparting to said pile-forming elements a further downward movement to force the embedding of the lower

free ends of said pile forming elements into the cementitious composition coating the backing.

2. An apparatus for producing a pile material, which comprises means for feeding a flexible backing, uniformly coated with a cementitious composition, to a pile forming station, means for feeding a supply of fiber elements to constitute the pile to a severing station, means for severing a predetermined length thereof from the fiber elements, and a plurality of means arranged in series comprising a plurality of pairs of jaws radially disposed for operative action on a rotating drum, for grasping said severed fiber elements in successive series thereof, and for moving such severed elements to a substantially vertical position with the lower free ends thereof at substantially right angles to and spaced from the point on the backing at which said pile-forming elements are to be deposited, at the same time another fiber grasping means is brought to a position adjacent the severing station, one of said pile grasping mechanisms being disposed at the pile forming station and being actuated to deposit the fiber elements upon the cementitious coating substantially simultaneously with the grasping by another pile grasping mechanism of a length of fiber elements at the severing station, and means for thereafter imparting to said pile-forming elements a further downward movement to force the embedding of the lower free ends of said pile-forming elements into the cementitious composition coating the backing.

3. An apparatus for producing a pile material, which comprises means for feeding a flexible backing, uniformly coated with a cementitious composition to a pile forming station, means for feeding a supply of fiber elements to constitute the pile to a severing station, means for severing a predetermined length thereof from the fiber elements, and a plurality of means arranged in series comprising a plurality of pairs of jaws radially disposed for operative action on a rotating drum for grasping said severed fiber elements and moving such severed elements to a substantially vertical position with the lower free ends thereof at substantially right angles to and spaced from the point on the backing at which said pile-forming elements are to be deposited, and means for grasping a successive length of fiber elements from the same source simultaneously with the depositing of the previously severed length upon the backing and means for thereafter imparting to said pile-forming elements a further downward movement to force the embedding of the lower free ends of said pile-forming elements into the cementitious composition coating the backing.

4. An apparatus for producing a pile material, which comprises means for feeding a flexible backing, uniformly coated with a cementitious composition to a pile forming station, means for feeding a supply of fiber elements to constitute the pile to a severing station, means for severing a predetermined length thereof from the fiber elements, and a plurality of means arranged in series comprising a plurality of pairs of jaws radially disposed for operative action on a rotating drum, for grasping successive lengths of fiber elements, and for moving such successive lengths of fiber elements to a substantially vertical position with the lower free ends thereof at substantially right angles to and spaced from the point on the backing at which said pile-forming elements are to be deposited, and there depositing the same upon the cementitious coating substantially simultaneously with the grasping by

another pile grasping mechanism of another length of fiber elements at the severing station and means for thereafter imparting to said pile-forming elements a further downward movement to force the embedding of the lower free ends of said pile-forming elements into the cementitious composition coating the backing.

5. An apparatus as claimed in claim 1, including means for intermittently advancing said drum.

6. In an apparatus for producing a pile material, of the type described, a pile transfer mechanism comprising an intermittently rotated drum, a plurality of pairs of jaws radially disposed for operative action on said drum said pile grasping means being disposed for successive operative movement to grasp successive portions of a supply of fiber elements and move the same successively to a position which they are deposited upon a cementitious coated flexible backing, and means for thereafter imparting to said pile-forming elements a further downward movement to force the embedding of the lower free ends of said pile-forming elements into the cementitious composition coating the backing.

7. In an apparatus for producing a pile material, of the type described, a pile transfer mechanism comprising an intermittently rotated drum, a plurality of pairs of jaws radially disposed for operative action on said drum, said pile grasping means being disposed for successive operative movement to grasp successive portions of a supply of fiber elements and move the same successively to a position in which they are deposited upon a cementitious coated flexible backing, and means for controlling the exact stoppage of rotation of the drum at a predetermined position in its rotation, comprising a shaft and a bumper hook pivotally secured thereto and adapted to engage appropriately positioned notches in the drum.

8. In an apparatus for producing a pile material, of the type described, a pile transfer mechanism comprising an intermittently rotated drum, a plurality of pairs of jaws radially disposed for operative action on said drum, said pile grasping means being disposed for successive operative movement to grasp successive portions of a supply of fiber elements and move the same successively to a position in which they are deposited upon a cementitious coated flexible backing, and means for locking the drum at predetermined points of its rotation.

9. In an apparatus for producing a pile material, of the type described, a pile transfer mechanism comprising an intermittently rotated drum, a plurality of pairs of jaws radially disposed for operative action on said drum, said pile grasping means being disposed for successive operative movement to grasp successive portions of a supply of fiber elements and move the same successively to a position in which they are deposited upon a cementitious coated flexible backing, and means for controlling the exact stoppage of rotation of the drum at a predetermined position in its rotation and means for locking the drum at such predetermined points of its rotation.

10. In an apparatus for producing a pile material in a continuous cyclic series of operation as claimed in claim 1, means for engaging the portion of the supply of fiber elements immediately rearwardly of its leading edge during its movement forwardly to the severing station, and means for releasing said engaging means, and moving the same rearwardly of the leading edge

of the pile forming elements after severance of a quantity of such elements from the supply.

11. In an apparatus for producing a pile material in a continuous cyclic series of operations a pile transfer mechanism comprising an intermittently rotated drum, a plurality of pairs of jaws radially disposed for operative action on said drum, said pile-grasping means being disposed for successive operative movement to grasp successive portions of a supply of fiber elements and move the same successively to a position in which they are deposited upon a cementitious coated flexible backing, a drum having a plurality of radially disposed fiber element grasping means, a cam disc rotatively supported with said drum, said disc having a plurality of notches in the periphery thereof, and a bumper hook, for engaging said notches.

12. In an apparatus for producing a pile material in a continuous cyclic series of operations, a pile transfer mechanism comprising an intermittently rotated drum, a plurality of pairs of jaws radially disposed for operative action on said drum, said pile grasping means being disposed for successive operative movement to grasp successive portions of a supply of fiber elements and move the same successively to a position in which they are deposited upon a cementitious coated flexible backing, a drum having a plurality of radially disposed fiber element grasping means, a cam disc rotatively supported with said drum said disc having a plurality of recesses in the periphery thereof, and a locking lever having a nose for engaging said recesses and thereby locking the drum against rotation.

13. An apparatus for making pile fabrics which comprises means to intermittently feed a backing having a cementitious coating thereon to a pile-depositing station, means to intermittently feed a pile-forming material to a severing station, a knife to sever the leading edge portion of said pile-forming material, a rotor provided with a plurality of grippers, means to intermittently rotate said rotor to dispose a gripper in position to grip the leading edge portion of said pile material prior to severance thereof and after severance to dispose said gripper at the pile-depositing station in a substantially vertical position with the lower ends of the pile elements spaced from and at right angles to the point on the coating at which said lower ends are to be embedded, said rotor having means to advance said gripper in a direction toward the pile material at the severing station, and means to move the gripper downwardly at the pile-depositing station whereby the pile elements are embedded in the coating and upwardly after the pile elements have been embedded in the coating.

14. An apparatus for making pile fabrics which comprises means to intermittently feed a backing having a cementitious coating thereon to a pile-depositing station, means to intermittently feed a pile-forming material to a severing station, a knife to sever the leading edge portion of said pile-forming material, a rotor provided with a plurality of grippers, and means to intermittently rotate said rotor to dispose a gripper in position to grip the leading edge portion of said pile material prior to severance thereof and after severance to dispose said gripper at the pile-depositing station in a substantially vertical position with the lower ends of the pile elements spaced from and at right angles to the point on the coating at which said lower ends are to be embedded, said

11

rotor having cam-controlled means to advance said gripper in a direction toward the pile material at the severing station, to move the gripper downwardly at the pile-depositing station whereby the pile elements are embedded in the pile coating, and to retract said gripper after the pile elements have been embedded in the coating.
